UNITED STATES PATENT OFFICE.

CHARLES ALEXANDER WATEROUS, OF BRANTFORD, ONTARIO, CANADA.

ELECTRIC GOVERNOR.

Application filed August 14, 1924, Serial No. 732,134, and in Canada October 15, 1923.

This invention relates to improvements in electric governors, and the objects of the invention are to provide a simple and effective device for maintaining a constant electrical condition on any motor or other device, whether such conditions consist in constant current, constant watts, or constant volt-amperes.

Further objects of the invention are to provide such a device as shall be immediately responsive to the variation in the electrical conditions observed, and one which will be sufficiently flexible to enable it to be applied to a variety of different purposes, if desired.

Further objects of the invention are to enable the device to be applied as a load controller on a motor-driven magazine or other pulp wood grinder, whereby an exact and constant regulation of the load may be effected.

Other specific objects of the invention will be apparent as the specification proceeds.

More general objects of the invention are to provide a device of this character in which the various co-operating parts will each efficiently perform the functions required of them.

In the construction, the invention includes an indicating electrical instrument, an electrical balance such as a Kelvin balance operating suitable contacts, two relays operatively connected with the contacts, two magnetically controlling valves suitably connected electrically, and a controlling member operated by the valves, all as hereinafter more fully set forth and described in the accompanying specifications and drawings.

In the drawings:

Figure 1 is a front elevation of an embodiment of the invention.

Figure 2 is a side view.

Figure 3 is a sectional side elevation.

Figure 3^A is a section detail of the dashpot device shown in Figure 3.

Figure 3^B is a detail partly in section of the piston rod and valve stem.

Figure 4 is a rear elevation, partially diagrammatic, showing the terminal boards and electrical connections.

Figure 5 is a front elevation of the electrical balance.

Figure 5^A is a sectional detail of the lower supporting means for the movable element.

Figure 6 is a side view of the balance.

Figure 7 is a plan view of the balance.

Figure 7^A is a detail view of the vertical shaft used in connection with the electrical balance.

Figure 8 is a side view of the contact member on the balance.

Figure 9 is a front elevation of the said contact member.

Figure 10 is a diagrammatic view, illustrating the electrical connections for the balance.

Figure 11 is a back view of the lower electrical terminal board.

Figure 12 is a side view of the lower terminal board.

Figure 13 is a front view of the lower terminal board.

In the drawings, like characters of reference indicate corresponding parts in all the views.

Referring to the drawings:

"A" indicates an indicating electrical instrument which may be of any standard type of wattmeter, voltmeter, ammeter, power factor meter, etc., according to the character of regulation desired. "B" indicates an electrical balance, shown as a Kelvin balance, especially wound to give maximum torque in proportion to weight, whereby, great relative rapidity of motion may be attained. The coils are designed according to the electrical quantity to be regulated, which may be potential, current, voltamperes, watts, power factor, frequency, etc.

"C" and "D" indicate relays controlled by the balance, and "E" and "F" are magnetically controlled valves controlled by the relays, and which in turn regulate the controlling device "G", the character of which will be described in detail hereinafter.

"H" indicates a suitable pedestal or frame, conveniently of cast iron, upon which the working parts are operatively connected, and which includes a box base 10, a central section 11, an upper compartment or box 12, and a case 13 for the electrical instruments, the sections 10, 11, 12 and 13 being conveniently formed separately and bolted or otherwise secured together as indicated, the lower section 10 being formed around the edge with an annular outwardly and upwardly extending flange 14 which extends to the supporting base and also serves to catch any oil drip.

The box base 10 carries a panel 15 usually of non-conducting material, on which the terminals and such fuses and resistances as

may be necessary are mounted. The Kelvin balance, shown in detail in Figures 5-9 (inclusive) will be wound for the service required, and is mounted upon a suitable panel 5 16 contained within the box 12. The balance comprises movable coils 17 and stationary coils 18. The number of turns and size of wire used will depend upon the nature of the electrical quantity to be regulated. The 10 stationary coils are mounted on posts 19, from the ends of which conducting leads are connected to the relays "C" and "D" mounted on the side of the pedestal.

The movable coils 17 are attached to a 15 light but rigid frame 20, usually made of sheet brass, but which may be made of any other suitable light and rigid material of a non-magnetic nature. To the top of this frame 20 is attached a threaded sleeve 21 of 20 Monel or other suitable non-corrodible metal. Around the upper end of the thread on the sleeve 21 is wound a suitable spring 22 of non-corrodible metal or suitably protected steel, which spring supports and controls 25 the moving coils 17 in opposition to the magnetic force acting between the movable coils 17 and the stationary coils 18. This spring thus forms a practically frictionless support for the moving coils as only molecular 30 friction is encountered in coiling or uncoiling a spring.

The upper end of the spring 22 is attached to the threaded portion of an upper sleeve 23, passing through a support 24 35 mounted on a panel 16. On the upper end of the sleeve 23 is mounted a worm wheel 25 actuated by a worm 26 which can be turned by a handle or thumb-nut 27 from the outside of the box 12. This worm and wheel 40 is used to vary the tension of the spring 22 and thereby determine or vary, if desired the amount of magnetic force necessary to maintain the moving coils 17 in equilibrium between the stationary coils 18. This 45 magnetic force is obtained by drawing from the machine to be regulated a suitable amount of current by means of transformers or other suitable devices.

Generally speaking, current coils if required are made to carry 5 amperes, and potential coils to carry 110 volts without overheating, but the balance described can be adapted to any reasonable conditions, the essential points being that the suspension be 50 nearly frictionless and the magnetic pull or push of the coils be large in proportion to the inertia of the moving parts.

To prevent backlash between the worm 26 and the worm wheel 25, a metallic block 28 60 is provided and pressed by a spring 29 against the worm 26. To further assist in holding the adjusting mechanism in position, a collar 30 is provided on the handle 27, a spring 31 extending between the collar 65 and the wall of the box 12. This will pre-

vent the handle turning too easily or jarring out of the value it is set at. In order to indicate the direction in which to turn the thumb nut 27 in order to vary the controlled quantity, such as watts, volts, amperes, etc., an indicating plate 33 is provided suitably graduated or marked to indicate the direction in which to turn the knob or thumb nut 27 in order to vary the controlled quantity. The variation obtained is observed by watching the indicating instrument A.

Returning to the frame 20, to the bottom of this a small bushing 34 is attached. Through this bushing and the upper bushing 80 21 passes freely the shaft 35 which is threaded at both ends into sleeves 36 and 37 carrying small springs 38 and 39 which pass freely through holes in the worm wheel sleeve 23 and in lower support 40 being held 85 in tension by pins 38^A and 39^A. The support 40 supports a compensator rod or lever 50 which is fitted with a boss fitting in a recess in support 40 thus being held centrally. This system of springs 38 and 39 together with 90 the shaft 35 and the supports referred to, acts as a guide to the frame 20, maintaining it in central position, thus forming a flexible and almost frictionless positioning means which is not likely to be injured during 95 shipment or handling.

To regulate the speed or movement of the frame 20 and to prevent needless vibrations thereof, a dashpot device is provided including an arm 41 projecting from the frame 20 100 and carrying a fan or blade 42 moving in a dashpot 43 filled with air or a suitable liquid designed to regulate the speed of movement as stated.

The Kelvin balance is designed to be regulated mechanically through the movement of the controlling member G which is communicated to it through the means presently to be described, and which include a bell crank lever 44 pivotally mounted on the panel 105 16 and having an operating link or rod 45 extending downwardly and connected to the controlling member by mechanism hereinafter described. The rod may be conveniently and adjustably connected to the bell crank 110 by means of a series of holes 46 in the arm of the bell crank to which the rod 45 is attached. The other arm of the bell crank is adjustably connected to an adjustable rod 47, as, for example by an eye or sleeve 48 with which the 115 rod 47 has screw-threaded engagement, the said eye or sleeve being connected to one of a series of perforations 49 in the bell crank.

The opposite end of the adjustable rod 47 is connected to the lever 50 which rests on the 120 lower support 40. The lever 50 is provided with a threaded hub 51 to which is attached the compensating spring 52 which extends upwardly and is attached to a threaded bushing 52^A. This bushing 52^A is provided with 125

two pins on its upper face so arranged as to engage in holes in the lower member of frame 20 with the object of transmitting the torque of the spring without causing any lateral displacement of frame 20. The end of the lever 50 is connected to a spring 53, the other end of which is adjustably attached to a bracket 54 as, for instance, by means of a threaded pin 55 connected to the spring and having screw-threaded engagement with the bracket.

The frame 20 carries suitable controlling making and breaking means, which means, as illustrated, include an arm 56 (see Fig. 8) carrying a suitable insulated stud 57 on which is mounted a wiper spring 58 carrying a suitable wiping contact point 59 swinging between adjustable stationary contact points fastened to rods 60 and 61 which can be adjusted to regulate the free swing of the contact 59. The contacts are usually made of platino-iridium. The small spring 58 gives a wiping action which keeps the contacts clean and makes sure contact. It is advisable, to avoid annoying repairs, that the current passing between these contacts be small, and the small spark can be further subdued by suitable high resistances 62 and 63 connected in parallel with the contact points.

From the stud 57 a flexible wire 64 runs to a terminal 65. From the adjustable stationary contact rods 60 and 61 conducting posts 19 lead to terminals 8 and 9 and from these by suitable wiring to the coils of the relays C and D. A current from an independent source of supply suitable for operating relays C and D is led by suitable wiring to terminal 65 and to the relay coils, and this current can thus be passed through or broken by the moving contact 59 as it swings between the adjustable stationary contacts 60 and 61. The movable coils 17 are connected through flexible leads to terminals 59^A, 60^A and 61^A as shown in Figures 8 and 9 and thence to the controlled machine or system. The stationary coils 18 are also suitably connected to the same controlled machine or system.

The relays C and D are conveniently mounted on the sides of the pedestal H as illustrated or they may be placed in any suitable location at any reasonable distance from the apparatus. These relays are similarly constructed.

When it is desired to control an electrical quantity through the intervention of a hydraulic piston rather than by electrical means exclusively, the current made and broken by the relays C and D is conducted by suitable wires to the magnetic valves E and F which may be placed in any suitable location not necessarily near the relays but to which they are connected by suitable conducting wires.

These valves each comprise a fluid-tight body or casing 80 of magnetic material pro-

vided with a cover 81 and are operatively connected to the control member G by suitable conducting conduits 105 through which the working fluid, usually oil, may pass, control valves 106 of any convenient design being provided for these conduits.

The control member G includes an operating piston 107 in a cylinder 108 the position of which is controlled by the magnetic valves E and F. One valve admits fluid under pressure to the underside of the piston and the other valve when open permits this fluid to escape. The working fluid under pressure is supplied by a pump equipped with suitable pressure regulating means and with a tank 80 to receive the fluid returned from the governor, all being of well known construction.

When the fluid is admitted to the underside of the piston 107 in the cylinder 108, the piston rises against the compression of a spring 109. This spring is made of considerable length to avoid great difference in pressure on the piston 107 in upper and lower positions. The spring is held by a suitable casting or sleeve 110 having threaded engagement with a supporting cover 111 which is bolted or otherwise secured to the top of the cylinder 108, the contacts being sufficiently tight to prevent any dust, etc., reaching the piston 107.

The piston 107 is preferably a ground fit in the cylinder 108 to thereby ensure prompt and positive action without undue friction. The piston is preferably grooved circumferentially, to reduce leakage. The fluid used is preferably incompressible, and the pressure available should be sufficient to promptly overcome frictional resistance so that the piston 107 will follow without excessive time lag, the indications of the measuring element as transmitted through the relays and magnetic valves.

To ensure smooth action without cutting or leakage, the piston 107 is made of ample length in proportion to diameter, and the spring force is applied at the centre of the bottom of the piston through a ball contact including a ball 112 held in the central seat 113 in the piston 107, and engaged at its opposite side by a pressure plate 114 against which a spring 109 bears.

The upward movement of the piston is limited in any suitable well known manner so that the upward limit of travel of the piston may be set and adjusted to suit the requirements of the controlling element that is to be moved by the piston.

To the piston 107 a piston rod 117 is connected by a flexible joint 118 which passes through a gland 119. The piston rod is preferably a ground fit in the gland, to reduce friction and which latter is grooved to prevent excessive leakage. The end of the piston rod is designed to be flexibly connected to the controlling element which may be a valve, a

brake, a rheostat, an adjustable condenser or any other controlling device that may be suitable for the service required.

In the embodiment illustrated in Figure 3, 5 the piston rod 117 is shown connected to the valve stem 120 of a special valve J suitable for controlling the speed of flow and consequently the pressure in a pipe line for a pulp wood grinder, thereby controlling the pressure 10 sure in the grinder, and consequently the power required to drive the same.

The valve J comprises a suitable body or casing 121 in which works a valve 122, the stem 120 of which is grooved circumferentially and is a ground fit in body so as to work freely with a small amount of leakage. Reduction of friction is more important in this case than reduction of leakage. The valve 122 itself is so shaped as to give a flow 15 proportional to the lift, thus avoiding sudden changes of flow which would increase the hunting tendency of the governor. This valve and stem should be made of durable material such as Monel metal, hard bronze or 20 stainless steel, or such other metal as is suitable for use with the fluid controlled.

The valve seat 123 is removable so that it can be replaced in case of wear and consequent excessive leakage. A set or stop screw 30 124 is provided in a removably threaded plug 125 beneath the valve seat designed to limit the downward travel of the valve to prevent it sticking on its seat, and to maintain a minimum rate of flow, as described. A suitable 35 cap 126 may be provided around the plug to prevent leakage or unauthorized adjustment of the stop screw.

The cylinder 108 and the valve casing are conveniently joined by a suitable junction 40 piece or member 127 which maintains proper alignment and distance between them. The end of the piston rod 117 and the valve stem 120 are rounded and touching so as to prevent incorrect alignment causing jamming of any 45 parts. Around the end of the piston rod 117 and the valve stem 120 is placed a loose sleeve 128 through which passes a pin 129 which is operatively connected to the Kelvin balance by the connecting means to be presently described.

These connecting means include a lever 130 connected by a free-working pin joint to the sleeve 128, said connection including the pin 129. The fulcrum of the lever 130 is made 55 adjustable, which is accomplished in the embodiment illustrated by forming the fulcrum on a sliding block 131 which can be adjusted in position by the screw 132 and knob 133, the latter projecting beyond the side of the pedestal H.

The end of the lever 130 opposite to that which is connected to the sleeve 128 is connected to a link 134, the opposite end of which is pivoted to a sliding dashpot 135 which 60 slides in a guide 136. Within the dashpot 135

is a piston 137 with a hole through its centre, this piston is connected to the hollow piston rod 140. A spring 138 extends between the fixed bracket 139 through a clearance hole in the cover of the dashpot to the piston 137 to which it is fastened to regulate the position and speed of movement of the piston. A rod 45^A is located inside the hollow piston rod 140. This rod 45^A is enlarged and tapered at the lower end so that when operated it gradually opens or closes holes 139^A through 70 the side of the hollow piston rod 140 by means of which the rate of flow of liquid from side to side of the piston 137 through the hole in the piston 137 and the holes in the hollow piston rod 140 may be varied. There is attached to the top of the hollow piston rod 140 a cap 163 threaded to fit the upper end of rod 45^A. To the upper end of rod 45^A is attached a knob 142 by means of which the rod 45^A can be 85 rotated and thereby raised or lowered in the hollow piston rod 140. To the cap 163 is attached a loop or other suitable connection engaging with rod or link 45 leading to bell crank 44 as previously described. The dashpot is filled with a suitable liquid to regulate the speed of movement of the piston 137 and the other moving parts connected thereto.

It will be seen that the dash pot device just described and the system of levers, referred to, transfer a portion of the movement of the piston rod 117 and the valve stem 120 back to the moving frame 20, the amount transmitted varying according to the extent and speed of movement of said piston rods, 90 and thereby preventing the swinging or over-running action of the regulator commonly known as hunting. The system of levers thus functions as a compensator and permits rapid governor action without over-running.

Figures 11 and 13 and 12 show the arrangement of the terminal board 15 which is mounted in the base box 10 and used to carry the terminals connected to the leads from the control machine. The arrangement and size of 100 these parts will vary with the quantity to be controlled and the specific manner in which the governor is applied. The arrangement illustrated is that required with the wattmeter type of governor which is applied to control 110 a pulp mill grinder or similar machine.

143, 144 and 145 are terminals connected to the potential supply of the grinder motor by means of suitable potential transformers. 146, 147 and 148 are fuses to protect governor 120 parts. 149, 150 and 151 are connections to resistances 152 and 153 and balancing resistances 154 which are used to supply proper and equal currents to the moving coils 17. 155 and 156 are resistances to control the potential supply to the indicating wattmeter A.

157, 158 and 159 are terminals to which are connected the current leads from current transformers in the main circuit of the controlled motor. Suitable wires run from ter- 130

minals 157 and 159 to short circuiting switches 160 and 161 which are used to short circuit the current transformers when starting motor or adjusting or repairing governor. From these 5 switches wires are run to the stationary wattmeter coils 18 of the Kelvin balance and also to the coils of the indicating wattmeter A.

The board shown is for three phase service, and a similar but differently arranged board 10 would be required for other service, such as two phase or direct current.

A sight glass 162 may be conveniently provided consisting in part of a glass tube whereby the rate of flow of the working fluid can be 15 inspected while the governor is in action.

It will be seen that, in operation, the moving coils are suspended by a spring which balances the torque when a desired quantity is being maintained. The resistance of the 20 spring can be varied by the fine adjustment, already described. Furthermore, the complete spring suspension and guide is of such a character as to be almost frictionless and not likely to be injured by variation or by 25 shock in shipping, and is designed to maintain its frictionless properties indefinitely.

Any unnecessary variation or fluttering is restrained by the vane 42 which enables practically dead beat regulation to be maintained. 30 The size and flexibility of the vane or paddle and the viscosity of the fluid may be varied to suit conditions.

The connection of the main controlling element to the Kelvin balance, as described, has 35 a compensating action which reduces overrunning or hunting.

It will be seen that in operation, the fluctuation in electrical quantity indicated by the balance B will cause energization of one or 40 other of the controlling relays C and D which, in turn, will operate one or other of the magnetically controlled valves E and F, which will operate the controlling element G as already described, the operation of which will 45 effect the desired regulation. In turn, the operation of the controlling element G, through the compensating levers already described, will mechanically affect the Kelvin balance to prevent overrunning.

50 As many changes could be made in the above construction and many widely different embodiments of my invention within the scope of the claims, constructed without departing from the spirit or scope thereof, it 55 is intended that all matter contained in the accompanying specification and drawings shall be interpreted as illustrative and not in a limiting sense.

What I claim as my invention is:

60 1. An apparatus of the character described comprising, in combination, an electrical balance, relays controlled thereby, magnetically controlled valves controlled by the relays, a controlling device operated by the 65 valves, mechanical connecting means between

the controlling device and the balance, including a lever with adjustable fulcrum.

2. An apparatus of the character described comprising, in combination, an electrical balance, relays controlled thereby, magnetically controlled valves controlled by the relays, a controlling device operated by the valves, and mechanical connecting means between the controlling device and the balance including a lever, an adjustable fulcrum block for the 75 lever, and a screw for adjusting the block.

3. An apparatus of the character described comprising, in combination, an electrical balance, relays controlled thereby, magnetically controlled valves controlled by the relays, a controlling device operated by the valves, and mechanical connecting means between the controlling device and the balance including a bell crank having one arm operatively connected to the controlling device 80 and one arm operatively connected to the electrical balance.

4. An apparatus of the character described comprising, in combination, an electrical balance, relays controlled thereby, magnetically controlled valves controlled by the relays, a controlling device operated by the valves, and mechanical connecting means between the controlling device and the balance including a bell crank having one arm operatively connected to the controlling device and one operatively connected to the electrical balance, and an adjustable spring connected 85 to the bell crank.

5. In an apparatus of the character described and in combination, an electrical balance having a suspending spring, a worm wheel connected thereto, an adjusting worm for the worm wheel, relays controlled by the balance, magnetically controlled valves controlled by the relays, and a controlling device 100 operated by the valves.

6. An apparatus of the character described comprising, in combination, an electrical balance, relays controlled thereby, magnetically controlled valves controlled by the relays, a controlling device operated by the valves, a fluid valve operatively connected to the controlling device, connecting means between the controlling device and the fluid 105 valve, and operating means extending from the said connecting means to the electrical balance.

7. An apparatus of the character described, comprising, in combination, an electrical balance, having a suspending spring, a worm wheel connected thereto, a spring held rod, a worm on the rod for the worm wheel, an operating knob on the rod, relays controlled by the balance magnetically-controlled valves controlled by the relays, and a controlling device operated by the valves.

8. An apparatus of the character described comprising, in combination, an electrical balance having a supporting and sus- 125

- pending spring, a worm wheel connected to the suspending spring, an adjusting worm for the worm wheel, a compensator rod connected to the supporting spring, relays controlled by the balance, magnetically controlled valves controlled by the relays, a controlling device operated by the valves, and a connection between the compensator rod and the controlling device.
9. An apparatus of the character described comprising in combination, an electrical balance having a supporting and suspending spring, a worm wheel connected to the suspending spring, an adjusting worm for the worm wheel, a compensator rod connected to the supporting spring, a spring held rod extending inside the two springs, relays controlled by the balance, magnetically controlled valves, controlled by the relays, a controlling device operated by the valves, and a connection between the compensator rod and the controlling device.
10. An apparatus of the character described comprising, in combination, an electrical balance having a supporting and suspending spring, a worm wheel connected to the suspending spring, an adjusting worm for the worm wheel, a compensator rod connected to the supporting spring, a horizontally extending resilient member connected to the compensator rod, relays controlled by the balance, magnetically controlled valves controlled by the relays, a controlling device operated by the valves, and a connection between the compensator rod and the controlling device.
11. An apparatus of the character de-
- scribed, comprising in combination, an electrical balance, including a hollow sleeve and a hollow hub, a worm wheel at the end of the sleeve, an adjusting worm for the worm wheel, a spring in the hollow sleeve and a spring in the hollow hub, means to retain the springs in their respective bores, a small sleeve carried by each of the springs, a rod joining the small sleeves, a suspending spring secured to the hollow sleeve, a supporting spring secured to the hollow hub, a compensator rod carrying the hollow hub, relays controlled by the balance, magnetically controlled valves controlled by the relays, a controlling device operated by the valves, and a connection between the compensator rod and the controlling device.
12. An apparatus of the character described comprising in combination, an electrical balance, relays controlled thereby, magnetically controlled valves controlled by the relays, a controlling device operated by the valves, and adjustable compensating connecting means between the controlling device and the valves including a dash pot device.
13. An electric governor comprising an electric balance, contacts operable by said balance, relays operatively associated with the contacts, magnetically controlled valves suitably connected electrically, a spring-pressed controlling member operable by the valves, and an indicating electrical instrument operatively associated with the balance.

In witness whereof I have hereunto set my hand.

CHARLES ALEXANDER WATEROUS.
